DESIGN FOR A HANDKERCHIEF

David E. Schwab, New York, N. Y.

Application November 1, 1937, Serial No. 72,556

Term of patent 3½ years

To all whom it may concern:

Be it known that I, David E. Schwab, a citizen of the United States of America, residing in the city of New York, county of New York, and State of New York, have invented a new, original, and ornamental Design for a Handkerchief, of which the following is a specification, reference being had to the accompanying drawing, forming part thereof.

The figure on the drawing is a plan view of a handkerchief showing my new design.

I claim:

The ornamental design for a handkerchief substantially as shown.

DAVID E. SCHWAB.
